R. B. GOODRICH.
VALVE LIFTER.
FILED MAY 22 1920.

INVENTOR:
Ralph Brown Goodrich

BY Allen & Allen
ATTORNEYS.

UNITED STATES PATENT OFFICE

RALPH BROWN GOODRICH, OF CINCINNATI, OHIO.

VALVE LIFTER.

Application filed May 22, 1920. Serial No. 383,513.

To all whom it may concern:

Be it known that I, RALPH BROWN GOODRICH, a citizen of the United States and a resident of the city of Cincinnati, in the county of Hamilton and State of Ohio, have invented certain new and useful Improvements in Valve Lifters, of which the following is a full, clear, and accurate description, reference being had to the drawings, forming part of this specification.

My invention relates to lever-like devices employed for the purpose of lifting up valves in internal combustion engines to permit of the springs thereon being detached, preliminary to grinding. Such devices, known as valve lifters, have been provided in the past in a variety of forms and my invention has as its object the simplification of the mechanisms and improvement 20 in modes of operation, in tools of this character.

Among other things it is my object to provide a pair of jaws, freely pivoting on the end of the operating lever and provided 25 with means for adjustably holding them together, which means is on the jaws as distinguished from being on the lever.

This object and other advantages to be noted I accomplish by that certain construction and arrangement of parts to be hereinafter more specifically pointed out and claimed.

In the drawings,

Figure 1 is a perspective view of the device in use.

Figure 2 is a perspective of the device on a larger scale.

Figure 3 is a plan view of the jaw device.

Figure 4 is a section on the line 4—4 of 40 Figure 3.

While my invention is specifically applied to valve lifters and will be so described, I do not wish its application to be limited to this use alone since its adjustable, 45 tong-like features adapt it to various additional uses.

The lever or bar 1 is provided in the valve lifter example of my invention which I have chosen as an illustration, and has a 50 handle 2 and a toothed or serrated under edge 3. A chain 4 is provided, said chain having at one end any desired means for providing an engagement with some engine part. At its other end is a hook 5 which is 55 adapted to engage the serrated lower edge

of the lever and provide the fulcrum for the lever.

The jaw device comprises a pair of jaw plates 6, 6, preferably having flanges or ribs 7 which are bent inwardly at their upper and lower edges to form tabs 8 and 9, that are perforated to engage a rivet 9a. This rivet passes through a boss 10 at the end of the lever and provides a pivot for the jaws. 65

The jaws swing on this pivot, both independently of each other for purpose of adjustment and simultaneously during operation.

The adjustment is provided by means of 70 the rearward extension 11, 11, of the jaw plate flanges. The extensions are slotted at 12 and ears 13, 14 are formed at the top and bottom of the slotted portions. These ears have holes therein and nuts 15 are 75 employed which are formed with pins 16, 17, extending from their upper and lower ends.

The pins are inserted in the holes in the ears, thereby providing a pivotal mounting for nuts and the nuts are right hand 80 and left hand threaded, respectively.

A right and left hand screw 18 is used which engages the nuts, and is operated by a fixed thumb piece 19, that lies between the jaw plate extensions, the screw being 85 free of the lever.

With this construction the jaws may be adjusted to engage any desired pieces, such as the spring 20 of a valve stem 21. The chain may be anchored to some engine part 90 as at 22, the lever fulcrumed on the hook, the jaws engaged under the spring, and the spring and valve lifted to permit the operator to disengage the spring from the valve stem. 95

The jaws may swing to permit any necessary clearances for the lever and the whole structure is inexpensive and desirable.

Having thus described my invention, what I claim as new and desire to secure 100 by Letters Patent, is:—

1. A device of the character described comprising a bar element, and a jaw element, means for pivotally mounting the jaw element to swing laterally on the bar 105 and means carried by the jaw element for adjusting the jaw opening thereof independent of the position of the bar.

2. A device of the character described, comprising a bar element and a jaw ele- 110

ment mounted thereon, said jaw element made up of two opposed independent jaw plates pivotally connected to each other and to the bar element to swing laterally and having extensions past the pivot point and means carried by the extensions for adjustably spacing them independently of the pivotal connection with the bar element.

3. A device of the character described comprising a bar element, and a jaw element, means for pivotally mounting the jaw element to swing laterally on the bar and means carried by the jaw element for adjusting the jaw opening thereof independently of the bar pivotal movement comprising pivotally mounted members on

the jaw members, and a screw engaging said pivotally mounted members whereby the pivotally mounted members will remain in alignment for engagement with the screw 20 in all positions of the jaw element.

4. A jaw structure comprising a pivot element, a pair of jaw plates pivotally secured to the pivot element and means carried by the jaws for spacing them adjustably with relation to each other, comprising a pair of nuts, means for pivotally mounting the nuts at their peripheries in the jaws and a right and left hand screw for engaging the nuts in the normal threaded 25 holes thereof.

RALPH BROWN GOODRICH.
